VANITY KIT

Louis Hernandez Campos, New York, N. Y.

Application February 1, 1943; Serial No. 474,261

7 Claims. (Cl. 132—83)

This invention relates to vanity kits of the type generally known as compacts. At the present time cases of this type are often fitted with powder compartments, mirrors and lipsticks that are designed to hold only one type of lipstick or rouge so that in many cases their usefulness ends when the lipstick or rouge is exhausted.

An object of this invention is to provide a case having provision for not only powder or rouge but also for lipsticks of any type desired and for tissues and other items. A further object is to provide a case of a class described in which the various items may be readily held in place so that they will not fall out or spill when the case is opened while at the same time the items may be readily removed from the case for use as desired. Other objects and advantages of my invention will become apparent as the description proceeds.

In the accompanying drawing

Figure 1 is a top plan view showing my case open.

Figure 2 is a cross sectional view of a case by my invention in a closed position.

Figure 3 is a cross sectional view taken on the line 3—3 of Figure 1.

Figure 4 is a perspective view of the powder and mirror carriage.

Figure 5 is a view of a slightly modified form of my invention.

Referring more particularly to the drawing, I provide a frame member 10 which may be made of metal, plastic, or any suitable material. In the form illustrated, frame 10 is provided with tabs 11 and 12, a bottom 13, and sides 14 and 15. The back portion 16 is rolled to form a round end and has a curved cutout portion 17 the purpose of which will be disclosed later. A cover 18 of leather or other suitable material is fastened to the base by means of the tabs 11 and 12. The tabs 11 and 12 also tend to support the back 16. Snap fasteners 19 and 20 may be provided to close the case.

A powder carriage 25 is provided and is adapted to slide within the walls 14 and 15. The carriage is constructed with a compartment 26, a cover 27 hinged at 28 and depending members 29 and 30 extending below the powder compartment. The cover 27 may be mirrored on both sides. Depending members 29 and 30 are bent out slightly as shown in Figures 3 and 4 to insure frictional resilient engagement with the walls 14 and 15 of the case member. It will also be noticed that the rear end 31 of the depending

members are cut away slightly so that the hinge 28 will overlie them considerably.

The powder carriage 27 is adapted to slide forwardly and rearwardly in the case as indicated by the arrow 32. Because of this feature, lipstick or rouge case 35 may be held between the end 33 of the carriage 25 and the end 16 of the case. Since the end 16 of the case is curved, it can accommodate any type or size lipstick that may be desired and if the lipstick furnished with the case is not satisfactory another may be substituted. Cover 27 is mirrored on both sides so that it may be used when the powder compact is opened or closed.

It is to be noted that the powder compact rests considerably above the bottom 13 of the case and a space is therefore provided for tissues 36 or cigarettes or other similar items. It will also be noticed that the end 16 of the base has a rounded cutout portion at 17. If desired the user may stand the lipstick or rouge case 35 vertically in this cutout portion and hold it by frictional engagement with the carriage 25 while the lipstick is in use.

In the modified form shown in Figure 5 the sidewalls 14 and 15 of case 10 are provided with a pair of elongated beads 40 and 41 to form internal grooves. The pintle 42 of the hinge 43 is slightly longer than the space between the walls 30 and engages the grooves formed by the beads 40 and 41 to limit the sliding movement of the carriage.

With my construction it is possible to carry lipstick or rouge, powder, mirror, and tissues or if desired cigarettes in a single compact case. Due to the fact that the cover 18 fastens over cover member 27, there is no danger of the powder compartment opening nor of the powder being spilled while the case is closed. The double mirror makes it possible to use the case with the powder compartment in either the opened or closed position. In view of the manner in which the lipstick is held in the case, any desired type of lipstick may be used.

I claim:

1. An article of the class described including a frame member having side and rear walls, a powder container slidably mounted between side walls and a lipstick frictionally held between said powder container and said rear wall.

2. A vanity case including a rigid body having side and rear walls, a powder container slidably mounted between side walls, said powder container having a cover constituting a mirror and being of a depth less than said side walls, depend-

ing members of said powder container adapted to slide on the bottom of said body defining with the bottom of said powder case a chamber.

3. An article of the class described including a frame member having both side and rear walls, said rear wall being curved to accommodate a lipstick, a powder container slidably mounted between said side walls adapted to hold a lipstick against said rear wall and a flexible cover therefor.

4. A vanity case including a rigid body having a bottom, side and rear walls, said rear walls being curved to conform to the shape of the lipstick, a powder container having depending walls adapted to space said container from the bottom of said body, said depending walls engaging the interior of said side walls, said powder container being adapted to slide within said body to position a lipstick against said rear wall.

5. A vanity case including a lipstick, mirror, powder box and tissue compartment, said powder

box having a cover constituting a mirror and being adapted to slide within the case to hold said lipstick in place.

6. A vanity case comprising a body having a bottom, side and rear walls, a flexible cover therefor, a powder box having depending walls adapted to engage the bottom and side walls of said body and to define therewith a compartment under said powder box, said powder box being slidable on said body and a lipstick positioned behind said powder box against said rear wall.

7. A vanity case including a rigid body having a bottom, side and rear walls, a powder box slidably mounted, between said side walls a lipstick positioned between said powder box and either rear wall, said rear wall being curved and having a cutout portion therein whereby said lipstick may be engaged in either a vertical or horizontal position.

LOUIS HERNANDEZ CAMPOS.
